UNITED STATES PATENT OFFICE

146,404

DESIGN FOR A RADIO CABINET

Robert Davol Budlong, Skokie, Ill., assignor to
Zenith Radio Corporation, a corporation of
Illinois

Application September 1, 1945, Serial No. 122,411

Term of patent 3½ years

(Cl. D56—4)

To all whom it may concern:

Be it known that I, Robert D. Budlong, a citizen of the United States, residing at Skokie, in the county of Cook and State of Illinois, have invented a new, original, and ornamental Design for a Radio Cabinet, in which the following is a specification, reference being had to the accompanying drawings, forming a part thereof, wherein:

Figure 1 is a front elevational view of a radio cabinet, with the door open, showing my new design;

Fig. 2 is an end view in perspective of the radio cabinet with the door open, as shown in Fig. 1;

Fig. 3 is a top plan view of the radio cabinet, with the door open, as shown in Fig. 1;

Fig. 4 is a perspective view of the radio cabinet with the door closed, showing my new design, and

Fig. 5 is a front perspective view similar to the view shown in Fig. 1 but with the antenna portion of the receiver removed from the door.

The dominant features of my design reside in the symmetrical dial and speaker grille sections shown in particular in Figures 1 and 5.

I claim:

The ornamental design for a radio cabinet, as shown and described.

ROBERT DAVOL BUDLONG.
